(57) **CLAIM**

The ornamental design for an infant nursing device, as shown and described.

DESCRIPTION

FIG. 1 is an exploded front elevational view of an infant nursing device showing my new design;

FIG. 2 is an exploded front orthographic view thereof;

FIG. 3 is a front elevational view of the inner container shown separately for completeness of illustration;

FIG. 4 is a side orthographic view of the inner container shown separately for completeness of illustration;

FIG. 5 is a side elevational view of the outer container shown separately for completeness of illustration;

FIG. 6 is a front orthographic view of the outer container shown separately for completeness of illustration;

FIG. 7 is a front elevational view of a cap for sealing the outer container shown separately for completeness of illustration;

FIG. 8 is a side orthographic view of a cap for sealing the outer container shown separately for completeness of illustration;

FIG. 9 is a side elevational view of a cap cover shown separately for completeness of illustration;

FIG. 10 is a side orthographic view of a cap cover shown separately for completeness of illustration;

FIG. 11 is a top plan view of a nipple with a side vent shown separately for completeness of illustration;

FIG. 12 is a side and front orthographic view of a nipple with a side vent shown separately for completeness of illustration;

FIG. 13 is a front elevational view of a nipple with a side vent shown separately for completeness of illustration;

FIG. 14 is a cross-sectional side elevational view of the nipple taken along the lines 14-14 of FIG. 13; and,

FIG. 15 is a bottom plan view of a nipple shown separately for completeness of illustration.
